United States Patent Office

Des. 227,879
Patented July 24, 1973

227,879

MODULAR HOUSING UNIT

Donald W. Modarelli, Jr., 908-A Peachtree Road,
Claymont, Del. 19703

Filed Sept. 13, 1971, Ser. No. 180,254

Term of patent 14 years

Int. Cl. D25—03

U.S. Cl. D13—1 A

FIG. 1

FIG. 2

FIG. 3

FIG. 4

FIG. 5

FIG. 1 is a front elevational view of a modular housing unit showing my new design;

FIG. 2 is a rear elevational view thereof;

FIG. 3 is a top plan view thereof;

FIG. 4 is a bottom plan view thereof; and

FIG. 5 is a side elevational view thereof.

I claim:

The ornamental design for a modular housing unit, substantially as shown in the drawing.
